ABSTRACT

An arrangement for toilet cupboard providing intense illumination of the lower part of the face for shaving or examining the skin, without the rays emitted by the source light being able to reach the user's eyes and dazzle him; the cupboard has a light chamber opening below an articulated frontal mirror and mechanical means to vertically displace said cupboard.

9 Claims, 5 Drawing Figures

ADJUSTABLE TOILET CUPBOARD WITH LIGHTING EQUIPMENT

It is known to associate a lamp with a toilet mirror, but known devices such as those described in U.S. Pat. Nos. 1,121,585, 1,606,870 and 2,853,594 for example give very unsatisfactory results: in fact, either they dazzle or they give insufficient illumination.

The device according to the present invention gives intense illumination of the lower part of the face for shaving or examining the skin, without the rays emitted by the source of light being able to reach the user's eyes and dazzle him.

The device according to the present invention consists of: a cupboard comprising a frontal mirror articulated at its base to a horizontal axis, a chamber situated at the base of the cupboard and opening below the mirror and comprising a source of light disposed at such a height as to be substantially in the horizontal plane of the axis of articulation of the said mirror; and eventually a mechanical device for enabling the said cupboard to be raised or lowered in order to adjust the height of the horizontal plane bounding the light beam.

The appended drawing is given by way of example and in order to facilitate understanding of the invention.

FIG. 1 illustrates a sectional view of a cupboard according to the invention.

FIGS. 2, 3 and 4 illustrate three variants of embodiment of the vertical sliding device.

FIG. 5 illustrates a view of an abutment for the shaft controlling the sliding action.

With reference to FIG. 1, it will be seen that the device comprises a cupboard M equipped with a frontal mirror 2 and two lateral mirrors 1. The lateral mirrors are articulated to vertical axes, while the frontal mirror is articulated to a horizontal axis 3. At the base of the cupboard there is a chamber N whereof the walls may be covered with nonreflecting paint.

In the chamber N there is a lamp 6 whereof the filament 0 is practically in the horizontal plane OB containing the axis 3.

In the chamber N, there is a diffuser screen 5, which may be movable, slightly in front of and below O. An additional screen 4 which is movable and articulated to the axis 3 is placed within said chamber.

The cupboard M is capable of sliding vertically along the support P, which in the example illustrated takes the form of a rack mechanism comprising two racks 8 with which there mesh the pinions 12 and 15 whereof the axes 30 are carried by the cupboard. According to a first variant, the pinion 12 is controlled by running gear in the form of a worm 10 actuated by a motor 9; according to a second variant, the pinion 15 is controlled by a worm 14 actuated by a crank 13. Axes 30 are, or may be, equipped with adjustable abutments.

The lamp 6 is controlled by way of a potentiometer 16.

Operating the crank 13 or the motor 9 displaces the cupboard M vertically in such a manner that the illuminated zone is bounded in its upper part by the horizontal plane OA, passing well below the eyes; while brightly illuminating the face. In order to give better protection to the eyes, the mirror 2 is inclined on the axis 3, thus inviting the user to raise his eyes as shown by VD.

For makeup purposes, screens diffuse the light and may be chosen to filter certain wavelengths while a linear lamp 7 disposed above the mirrors provides moderate supplementary illumination of the top of the face, ambient lighting and extra tanning effect.

The potentiometer adjustment makes it possible to increase

infrared emission for skin hygiene, reduce shaving soreness and facilitate cutting the beard.

FIGS. 2, 3 and 4 illustrate three variants of the vertical sliding device, the racks 8 being carried by profiled pieces 22 comprising one or more channels 21 in which there circulate one or more balls 20 located in ball cups 23 in the blocks 17 for the walls 18 or in a recess 24 (FIG. 4).

With reference to FIG. 5, it will be seen that the axis 30 is provided with a recess 31 in which there is a ball 32 retained by a screw 35 carried by a nut 34 fast with the block 17.

The mechanism serving to impart vertical displacement to the cupboard may be of the counterweight type.

I claim:

1. Lighting device formed by a cabinet, comprising:
a mirror;
a chamber situated at the base of said cabinet and opening beneath said mirror;
a luminous source arranged inside said chamber and disposed substantially in the horizontal plane of the base of the mirror; and
a mechanical device to which said cabinet is secured, said mechanical device effective to vary the height of the cabinet in order to adjust, in accordance with the height of a user, the height of said horizontal plane which delimits the zone lighted by said luminous source lamp.
2. Device according to claim 1, in which the mirror is articulated according to a horizontal axis.
3. Device according to claim 1, in which the chamber comprises a first screen situated slightly ahead of and below the luminous source.
4. Device according to claim 3, wherein said chamber further comprises a second screen articulated along a horizontal axis situated substantially at the level of the base of the mirror, said first and second screens being of the diffusing and filtering type.
5. Device according to claim 1, in which the chamber comprises a second screen articulated along a horizontal axis situated substantially at the level of the base of the mirror.
6. Device according to claim 1, wherein the height adjusting mechanism is a rack mechanism.
7. Device according to claim 6, wherein said rack mechanism is equipped with running gear.
8. Device according to claim 6, wherein the rack mechanism comprises a worm whose axis is equipped with an adjustable abutment.
9. Lighting device formed by a cabinet, comprising:
a mirror;
a chamber situated at the base of said cabinet and opening beneath said mirror;
a first luminous source arranged inside said chamber and disposed substantially in the horizontal plane of the base of the mirror;
a mechanical device to which said cabinet is secured, said mechanical device effective to vary the height of the cabinet in order to adjust, in accordance with the height of a user, the height of said horizontal plane which delimits the zone lighted by said luminous source lamp,
a first screen situated slightly ahead of and above the luminous source;
a second screen articulated along a horizontal axis situated substantially at the level of the base of the mirror; and
a second luminous source located at the top of the cupboard said second luminous source being a linear lamp providing ambient illumination.
